ATTORNEY

UNITED STATES PATENT OFFICE.

OSCAR HOCHBERG, OF NEW YORK, N. Y., ASSIGNOR TO AMERICAN CAR AND FOUNDRY COMPANY, OF NEW YORK, N. Y., A CORPORATION OF NEW JERSEY.

GENERAL-SERVICE RAILWAY CAR.

Application filed November 1, 1921. Serial No 511,992.

To all whom it may concern:

Be it known that I, OSCAR HOCHBERG, residing at New York, in the county and State of New York, and being a citizen of the 5 United States, have invented certain new and useful Improvements in General-Service Railway Cars, of which the following is a full, clear, and exact description, such as will enable others skilled in the art to 10 which it appertains to make and use the same, reference being had to the accompanying drawings, which illustrate the preferred form of the invention, though it is to be understood that the invention is not limited 15 to the exact details of construction shown and described, as it is obvious that various modifications thereof within the scope of the claims will occur to persons skilled in the art.

20 In said drawings:

Figure 1 is a plan of a portion of a car equipped with a door-operating mechanism constructed in accordance with my invention;

25 Figure 2 is a vertical sectional view taken on line 2—2 of Fig. 3, looking in the direction indicated by the arrow;

Figure 3 is a vertical sectional view taken on line 3—3 of Fig. 1, looking in the direction indicated by the arrow and showing the door in locked and complete closed position;

30 Figure 4 is a similar view showing the door locking mechanism in position just prior to the unlocking operation when the parts move to the position indicated in broken lines;

35 Figure 5 is a similar view showing the door locking parts in position with the door relatively closed and locked;

Figure 6 is a side view of one of the automatic gravity latches carried by the doors; and

40 Figure 7 is a front elevational view of one of said gravity latches.

One object of my invention is to provide a general service railway car in which a plurality of drop doors are adapted to be manually and severally raised and automatically locked, and simultaneously released.

45 Another object is to provide a mechanism for locking the drop doors in closed and relatively closed positions.

50 A further object is to provide means for simultaneously raising the doors from a

locked and relatively closed position to a locked and fully closed position.

A final and important object is to provide a mechanism in which the door locking parts function independently during the 60 first stage of the door raising operation and simultaneously during the final closing movement thereof.

In said drawings, 10 represents the center sill of the car, 11 the cross framing members, 12 a side wall, and 13 designates one of the drop doors hinged at the center sill and closing the opening between said car framing members. Secured to the doors 13 at their free edges are gravity locking latches 14 suspended from brackets 15 or the like by pins 16 and adapted to automatically engage door supporting means hereinafter referred to.

Cooperating with the gravity latches 14 75 on the doors and supported in extended bearings 17 at the ends of the cross framing members 11, is a door supporting shaft 18 adapted for lateral movement to and from a position under the doors. For effecting such lateral movement, said shaft is provided with radially disposed fingers 19 adapted for engagement with latches 14. The shaft is movable upon engagement of fingers 19 with one of the faces on latches 85 14, the direction of such movement being opposed to the direction of rotation of said shaft. During the closing movement of the doors said shaft moves inwardly from the car side and in the opposite direction to 90 release said doors.

In all positions of shaft 18, whether under the doors 13 or beyond the free edges thereof, gravity latches 14 will at all times automatically engage said shaft and lock said doors when the doors are raised. To insure proper seating of the gravity latches 14 upon shaft 18 when the doors are raised, the latches are formed with normally protruding shaft bearing portions 20 designed to 100 rest upon the shaft and terminating in shaft bearing extensions 21 for limiting outward movement thereof. For limiting inward movement of said latches they are provided with inwardly projecting arm portions 22 designed to abut adjacent portions of the door.

105 Fingers 19 are designed to adapt one side thereof for interlocking with an inner face 23 on the latches, the opposite side thereof 110

presenting a bearing surface for engaging a normally inclined outer face 24 on the latches. The interlocking sides of fingers 19 are formed as shown at 25 to enter recess 26 on inner faces 23 on the latches 14. The interlocking of latch and finger is complete upon contact of shaft 18 with shaft bearing extensions 21 on the latches and engagement of finger portions 25 within latch recesses 26. Thus positioned, a positive and rigid connection between shaft fingers and door latches is achieved. The opposite sides 27 of fingers 19 are formed to bear against the outer face 24 on the latches at a point 15 below pivot pins 16 to urge shaft 18 outwardly from under said latches.

To facilitate the manual operation of the doors 13, I provide a loop piece 28 on the underside of each door a short distance back 20 of the free edges thereof as in Figs. 1 and 3, adapted to receive the end of a temporary bar 29 to afford additional leverage against possible obstruction to door raising movement. The bar is braced against the under- 25 side of a door stiffener 30 during the door raising operation to permit the door to pass above the shaft and prevent the bar from striking said shaft. The loop 28 is large enough to permit the shifting of the lifting 30 bar to either corner of the door in the event of the sagging of the door at these points to insure the proper seating of latches 14 upon the shaft.

In operation, if it is desired to lock the 35 doors in the fully closed position shown in Figs. 1 to 4 inc., the doors are first raised by hand, using bar 29 if necessary, until the latches 14 seat with their shaft bearing portions 20 upon the shaft 18 which, at this 40 stage of the operation, occupies the outer end of the elongated bearing 17 as shown in Fig. 5. With the shaft in this position and the latches 14 resting thereon, the door will occupy the relatively closed position shown 45 in this figure. During the progress of door movement to such relatively closed position, the latches 14 will engage shaft 18 along their inclined outer faces 24 and be forced inwardly until said faces clear the shaft whereupon 50 said latches will swing outwardly by gravity until their shaft bearing portions 20 are firmly seated upon the shaft and the door locked. With the latches thus seated upon the shaft the door will be locked in a 55 relatively closed position and in condition to be raised to its final and fully closed position. As soon as the doors are raised and their latches mounted on the shaft, any subsequent movement of said shaft will be 60 transmitted to such latches simultaneously.

To raise the locked relatively closed doors to their fully closed position, the shaft 18 is rotated by means of any suitable operating means (not shown) in a direction 65 away from the free edge of the door as in-

dicated by the arrow in Fig. 5, until portion 25 of finger 19 on the shaft nests within recess 26 on inner face 23 of latch 14. Upon continued rotation of the shaft said finger will press upon the latch to cause same to 70 bear with its extension 21 against the shaft, forming in effect a rigid crank-arm mounted upon shaft 18 and taking pin 16 on the door. With the latch 14 functioning as a crank-arm, further rotation of shaft 18 will cause 75 said shaft to be moved inwardly toward the door, forcing said door upwardly to the fully locked and closed position shown in Fig. 4. Upon consummation of such movement, shaft rotation will cease upon contact 80 of latch projecting portion 22 with an adjacent part of the door.

It will be noted that in their final locked position the latches 14 and fingers 19 function to transmit the load on the doors directly to the shaft. In such position of the parts, the doors are wedged up and locked, the wedging effect being produced by the movement of the shaft towards the door. During such movement of the shaft, the 85 crank arms thereon, made up of the latches and fingers aforesaid, will move from the inclined position indicated in Fig. 5 to the vertical position shown in Fig. 4 producing a powerful wedging action upon the doors 90 throughout their final closing movement.

To release the doors the shaft is rotated in a direction toward the free edge of the door as indicated by the arrow in Fig. 4. As the shaft is rotated, finger portion 25 will 100 draw away from recess 26 on the inner face 23 of latch 14 and continue to move until the opposite side 27 of finger 19 engages the outer face 24 on the latches. During such period of rotation the shaft is held at the 105 innermost end of elongated bearings 17, the tendency for the shaft to move in the direction of rotation thereof being prevented by the latches 14 held against inward movement by latch arms 22 abutting the doors. Upon 110 engagement of finger portions 27 and latch faces 24, continued rotation of shaft 18 will cause said shaft to be moved outwardly from under latches 14 and out of the path of the free edge of the door 13, permitting said door to drop to the broken line position indicated in Fig. 3.

With the mechanism described, permanent connections between doors and shaft are dispensed with, and the doors are automatically and positively locked when severally raised, relieving the operator from any necessity for manipulating locking devices while holding the doors. The shaft is movable into final door supporting position 120 through the medium only of the door latches independently of any part on the car framing, said latches uniting with the shaft fingers to form rigid crank-arms fixed to the supporting shafts. 125

What I claim is:

1. In a door operating mechanism, the combination comprising a hinged door, separate supporting means therefor, and locking latches pivotally mounted on said door adapted to swing by gravity into position for initially engaging said supporting means and to subsequently interlock and move with said means to completely close said door.
2. In a dump car, a plurality of drop doors forming the floor of said car and adapted to be manually and severally raised, gravity latches depending from said doors, and door supporting means in position to initially engage said latches, said supporting means being movable with said latches to subsequently close said doors.
3. In a general service railway car, manually and severally operable drop doors carrying pivoted locking latches at their free edges, said latches being adapted to automatically lock said doors when raised, and separate movable door supporting means adjacent said doors in position to be moved outwardly from under said latches for subsequently releasing said doors.
4. In a dump car, manually and severally operable drop doors carrying gravity locking latches at their free edges, and separate door supporting means adjacent said doors adapted to engage said locking latches for simultaneously closing said doors, said latches operating to automatically engage the door supporting means upon the raising of said doors.
5. In a door operating mechanism for general service railway cars having a plurality of drop doors, door supporting mechanism extending along the car side and adjacent the free edges of said doors, gravity locking latches carried by the doors adapted to automatically engage said supporting mechanism for locking said doors in a relatively closed position, said latches being movable with said supporting mechanism to completely close said doors.
6. In a general service railway car comprising framing members and manually and severally operable drop doors closing the openings between said members, a door supporting shaft movably supported in said framing members adjacent the free edges of said doors, and gravity latches carried by the doors adapted to automatically engage said supporting shaft for locking said doors when raised.
7. In a general service railway car comprising framing members and manually and severally operable drop doors closing the openings between said members, a door supporting shaft movably supported in said framing members adjacent the free edges of said doors, and gravity latches carried by the doors designed to automatically engage said supporting shaft for locking said doors in a relatively closed position, said latches being movable with said supporting shaft to completely close said doors.
8. In a door operating mechanism for cars having a plurality of manually and severally operable drop doors supported at their free edges when raised, a separate door supporting shaft supported on the car framing adjacent the free edges of said doors, and means on the shaft adapted for engagement with a movable door part to laterally move said shaft.
9. In a general service railway car having a plurality of manually and severally operable drop doors supported at their free edges when raised, a separate door supporting shaft on the car framing adjacent the free edges of said doors, pivoted locking latches carried by said doors at the free edges thereof, and means on said shaft designed for inter-locking engagement with said latches for laterally moving said shaft.
10. In a general service railway car comprising framing members and manually and severally operable drop doors closing the openings between said members, a door supporting shaft movably supported in said framing members adjacent the free edges of said doors, gravity latches carried by the doors designed to automatically engage said supporting shaft for locking said doors in a relatively closed position, and means on the shaft adapted for subsequent interlocking engagement with said latches to laterally move said shaft.
11. In a door operating mechanism for cars having a plurality of manually and severally operable drop doors supported at their free edges when raised, a separate door supporting shaft movably supported on the car adjacent the free edges of said doors, gravity latches carried by the doors adapted to automatically engage said supporting shaft for initially locking said doors, and means on said shaft for subsequently establishing connection with said latches.
12. In a general service railway car having a plurality of manually and severally operable drop doors carrying gravity locking latches at their free edges, a separate door supporting shaft in position to engage said latches upon raising of the doors, and rigid finger elements on said shaft in position to engage said latches for laterally moving said shaft.
13. In a door operating mechanism for cars including a rotatable and laterally movable door supporting shaft mounted in extended bearings on the car framing, drop doors arranged with their free edges adjacent said shaft and adapted to be manually and severally raised, gravity locking latches carried by the doors in position to laterally move said shaft.

to automatically engage said shaft when the doors are raised and to support said doors in a relatively closed position, and rigid finger elements on said shaft uniting 5 with said latches to laterally move said shaft for completely closing said doors.

14. In a door operating mechanism for cars having a plurality of manually and severally operable drop doors supported at 10 their free edges when raised, a separate door supporting shaft supported on the car framing adjacent the free edges of said doors and adapted to support the doors in a plurality of positions, and pivoted locking latches carried by said doors in position to automatically engage said shaft to lock said doors in a relatively closed position, said latches being designed to cause lateral movement of said shaft to completely close said doors.

15. In a dump car, a plurality of drop doors forming the floor of said car and adapted to be manually and severally raised, pivoted latches depending from said doors, 25 and a door supporting shaft in position to initially engage said latches, said shaft having latch engaging fingers adapted to unite with said latches to provide a connection with said doors.

30 16. In a door operating mechanism, the

combination comprising a hinged door, locking latches pivotally mounted on said door, a movable door supporting shaft having latch engaging fingers, said fingers being adapted to rigidly unite with said latches to connect said door and shaft.

17. In a door operating mechanism including a door supporting shaft movably mounted adjacent the free edge of the door, a drop door provided with a depending latch pivotally mounted on said door in position to engage the shaft, and a finger piece on the shaft formed to unite with said latch to provide a rigid connection between said door and shaft.

18. In a door operating mechanism including a door and a movable supporting shaft, pivoted latches on the door adapted to initially engage said shaft upon the raising of the door to a relatively closed position, and fingers on the shaft designed to complement said latches to form a rigid crank-arm connection adapted to move said shaft to completely close said door.

In witness whereof I have hereunto set my hand in the presence of two witnesses.

OSCAR HOCHBERG.
